UNITED STATES PATENT OFFICE.

PETER A. PAUL, OF LEWISBURG, OHIO.

PUSH-BUTTON SWITCH.

No. 887,840.

Specification of Letters Patent. Patented May 19, 1908.

Application filed August 15, 1907. Serial No. 388,709.

To all whom it may concern:

Be it known that I, PETER A. PAUL, a citizen of the United States, residing at Lewisburg, in the county of Preble and State of Ohio, have invented a new and useful Push-Button Switch, of which the following is a specification.

This invention has reference to improvements in push-button switches, and its object is to produce a push-button switch of either the wall type or the pear type wherein a bridging conductor is forced into contact with circuit terminals by a cam mechanism and the circuit is broken by the resiliency 10 of the bridging conductor, whereby the latter is caused to break the circuit when relieved from the action of the cam mechanism.

The invention comprises a suitable casing adapted to the purposes for which the switch 20 is to be used, which casing carries spaced circuit terminals and also a bridging conductor sufficiently elastic and having a normal tendency to move away from the circuit terminals so as to break the circuit. The 25 bridging conductor has its elastic members opposed to each other and their normal tendency is to approach each other. Between the arms of the bridging conductor there is interposed a cam block, which may or may 30 not be of insulating material, and this cam block is mounted upon a shaft or spindle so as to be free to rotate thereon. The shaft or spindle carries a push-button and is also provided with helical grooves of long pitch 35 engaging tongues in an impelling member, which member is provided with suitable teeth or projections arranged to engage teeth or projections upon the contiguous face of the cam block with which the impelling member 40 engages, while a spring upon the shaft or spindle holds the two blocks in yielding engagement.

Now, when the push-button is forced in the proper direction the impelling member is 45 caused to rotate by the longitudinal movement of the shaft, since the shaft is held against rotation and has longitudinal movement only. The rotative movement of the impelling member causes the latter to engage 50 the cam block and, in turn, rotate it so as to bring it into engagement with the elastic members of the bridging conductor in such manner that these elastic members are caused to recede one from the other and 55 ultimately come into engagement with the

circuit terminals, thus completing the circuit at this point.

The cam block is so shaped as to automatically lock at certain points in its rotative movement by its engagement with the elastic members of the bridging conductor, and when the shaft or spindle is returned to its normal position by the action of the spring surrounding it, it will reverse the movement of the impelling or actuating 60 member and bring the same into a new operative relation to the cam block. Under these conditions, when the push-button is again moved in the proper direction, the cam block is also moved to a position where the 65 spring elements of the bridging conductor are permitted to move away from the circuit terminals and thus break the circuit.

The invention will be fully understood from the following detailed description, 70 taken in connection with the accompanying drawings forming part of this specification, in which,

Figure 1 is a longitudinal section of the improved push-button switch when adapted to be inserted in a wall; Fig. 2 is a cross section on the line x—x of Fig. 1, looking toward the left of said figure; Fig. 3 is a cross section on the line y—y of Fig. 1, looking toward the right of said figure; and Fig. 4 is a side elevation of a push-button switch of the pendent 80 pear type, constructed in accordance with the present invention.

Referring to the drawings, there is shown in Fig. 1 a casing 1 of insulating material, 90 preferably refractory material such as porcelain, and suitably shaped to receive the various parts constituting the improved push-button of the present invention and adapted particularly for insertion in a wall or panel. 95 To one end of the casing or block 1 there is secured a face-plate 2 by means of screws 3, and a centrally located passage 4 extends through the face-plate and corresponding end of the block 1 to an interior chamber 5 within 100 the block.

The chamber 5 is open at the sides and these openings are closed by removable insulating plates 6, slidably in grooves 7 in the unbroken walls of the casing or block. The 105 plates 6 may be of any suitable material but mica is preferred, since by the use of this material the interior of the push-button, that is, the parts contained within the chamber 5, may be examined without removing the 110

plates 6, whereby it may be ascertained what, if any, repairs are necessary, without first removing the plates 6.

At the end of the casing 1 remote from the face-plate 2 there are insulated metal blocks 8 spaced wide apart, and from these blocks extend strips 9 terminating in contact points 10 constituting the interior terminals of the push-button. The strips 9 lie against the unbroken walls of the casing and are opposed one to the other, being separated by a space a little less than the width of the chamber 5 at this point. The blocks 8 have longitudinal perforations for the introduction of conductors 11 coming from a source of electrical energy, and these conductors are held in place by binding screws 12 or otherwise.

Secured to the casing within the chamber 5 at the end toward the plate 2 is a bridging conductor 13 consisting of a metallic plate of sufficient size to safely conduct the current, and extending from this plate toward the other end of the chamber 5 are two arms 14, one adjacent to each side of said chamber and arranged to make contact with the contact points 10 of the strips 9. The arms 14, however, are elastic and have a normal tendency to approach each other and to remain out of contact with the points 10, which latter are so located as to contact with the arms 14 about midway of the length of said arms. The arms 14 extend nearly to the other end of the chamber 5, and between them is located a cam block 15 mounted upon a shaft or spindle 16 extending centrally through the casing 1 and also through the passage 4 and carrying at the end adjacent to the plate 2 a button 17 of suitable material whereby the shaft or spindle 16 may be moved longitudinally. Movement of the shaft 16 in a direction to project the button 17 out from the plate 2 is limited by a washer or flange 18 formed or secured on the end of the shaft 16 which projects beyond the rear or back end of the casing 1. The shaft 16 for the greater portion of its length may be circular in cross section, but where it projects through the plate 13 this shaft is substantially rectangular, as indicated at 19, and the orifice through the plate 13 through which this shaft extends is similarly shaped, so that while the shaft may be freely moved longitudinally for the distance provided it cannot turn upon a longitudinal axis.

Since the plate 13 constitutes part of the bridging conductor, the orifice through which the portion 19 of the shaft 16 extends may be of insulating material, as indicated at 20, although since it is usual to make the button 17 of insulating material and the casing 1 of porcelain, it is not absolutely necessary that this insulation 20 be introduced. If, however, the cam block 15 is also made of insulating material, then no current can reach the shaft 16 and thus there is no danger whatsoever of a

person using the push-button receiving a shock through faulty insulation of the button 17.

The cam block 15 is rotatable upon the shaft 16 and is shown as rectangular in outline, and has a greater diameter in one direction than in a direction at right angles thereto, while the corners of the block are rounded, as indicated. On one face of the block there is formed a hub 21 bearing against the corresponding end of the casing 1, while the other face of the block is formed into two pairs of teeth 22 and 23, the teeth of each pair being diametrically opposed. The surface of each tooth 22 and 23 is inclined up to the shoulder of the tooth. Resting upon the face of the cam block 15 is an impelling member 24 having diametrically opposed wings 25 so disposed as to engage the shoulders of the pairs of teeth 22 or 23, as the case may be, so that when the impelling member or block is given a rotary motion the cam member is constrained to move with it by the engagement of the wings 25 with the shoulders of the teeth 22 or 23, but when the impelling member is rotated in a direction opposed to that just considered, these wings 25 will ride up the inclined surfaces of the teeth and drop off the shouldered ends of the teeth on to the inclined surfaces of the next pair of teeth.

The impelling member 24 is mounted upon the shaft 16, but this shaft at this point is provided with opposed helical grooves 26-26 in which engage tongues 27 on the block or impelling member 24. The grooves 26 are of long pitch, so that the extent of travel of the shaft 16 in a longitudinal direction will be sufficient to cause the rotation of the impelling member 24 through an arc of about ninety degrees.

Surrounding the shaft 16 between the impelling member and a fixed flange 28 on the shaft is a helical spring 29 which is always under sufficient tension to maintain the impelling member in constant engagement with the face of the cam block, and which is compressed by the movement of the shaft 16 in a direction to cause the flange to approach the impelling member. The tendency of the spring 29 is to always maintain the shaft in a position to project the button 17 to its fullest extent beyond the face of the plate 2, at which point the flange 18 is in engagement with the corresponding end of the casing 1.

The inward tendency of the two arms 14 is such that these arms are brought into engagement with the longer sides of the cam block 15 located on its shorter diameter and in which position the arms 14 are out of contact with the terminals 10.

Now, let it be assumed that pressure is applied to the button 17 to move the shaft 16 longitudinally against the action of the spring 29. The cam block 15 is elastically locked by the engagement of the arms 14 with its

longer sides, but the impelling member 24 is constrained to rotate by the helical grooves 26 which are in engagement with the tongues 27. The direction of rotation of the impelling member 24 is such that the wings 25 are brought into engagement with the shoulders of the teeth 22 or 23, as the case may be. As the longitudinal movement of the shaft 16 continues the impelling member forces the cam block 15 in the same direction until the shorter sides, located upon the longer diameter of the block 15, are brought into engagement with the arms 14. In the meantime these arms have been moved apart by the increasing diameter of the block 15 and are brought into firm engagement with the terminals 10. In fact, these arms 14 are brought into engagement with the terminals 10 before the movement of the block 15 is completed and are therefore held in such engagement under considerable stress, so that there is no danger of the accidental breaking of the circuit at this point under sudden shocks or jars.

Now the circuit from the conductors 11 is completed through the blocks 8, strips 9, terminals 10, arms 14 and plate 13, the plate 13 and arms 14 constituting the bridging conductor. When the button 17 is released the spring 29 returns the shaft to its initial position. In so doing the grooves 26 act in a contrary manner upon the tongues 27 and cause the reverse movement of the impelling member 24, thus causing the latter to ride over the inclined faces of the teeth and ultimately drop behind the shoulders of such teeth. The slight longitudinal movement of the impelling member 24 necessary to ride up the inclined surfaces of the teeth is permitted by the yielding of the spring 29, but the frictional engagement of the impelling member with the block 15 is not sufficient to rotate the latter against the locking action of the arms 14 then engaging the shorter sides of the block 15 on its longer diameter.

When the push-button is again manipulated the block 15 is turned through an arc of ninety

degrees, again bringing its longer sides or shorter diameter in line with the arms 14, thus permitting these arms to recede from the contacts 10 because of their normal tendency to make this movement.

In Fig. 4 the invention is shown applied to a push-button switch of the pear type, and in this case the interior mechanism of the push-button may be always visible through the transparent insulating side plates 6. Otherwise, except in the shape of the casing, the parts are similar to those shown in the other figures.

I claim:

1. A push button switch comprising a longitudinally movable but non-rotatable shaft having helical grooves of long pitch, a cam block mounted on said shaft, an impelling block also mounted on the shaft and engaged by the grooves thereof, said impelling block and cam block being provided with one-way engaging faces, a spring for holding the impelling block in engagement with the cam block, circuit terminals, and means engaged by the cam blocks and movable thereby to close the circuit at the circuit terminals.

2. A push-button switch comprising a longitudinally movable but non-rotatable shaft having helical grooves of long pitch, a cam block mounted on said shaft and having teeth on one face, an impelling block also mounted on the shaft and engaged by the grooves therein, said impelling block having wings engaging the teeth on the cam block, a spring for holding the impelling block in engagement with the cam block, circuit terminals, and a bridging contact in operative relation to the cam block and movable thereby into engagement with the circuit terminals to complete the circuit therethrough.

In testimony that I claim the foregoing as my own, I have hereto affixed my signature in the presence of two witnesses.
